UNITED STATES PATENT OFFICE.

JOHN WILLS CLOUD, OF ALTOONA, PENNSYLVANIA.

FUEL-FEEDING DEVICE FOR LOCOMOTIVES.

SPECIFICATION forming part of Letters Patent No. 289,226, dated November 27, 1882.

Application filed March 7, 1883. (No mod. 1.)

To all whom it may concern:

Be it known that I, JOHN W. CLOUD, of Altoona, county of Blair, State of Pennsylvania, have invented or discovered a new and useful Improvement in Fuel-Feeding Devices for Locomotives; and I do hereby declare the following to be a full, clear, concise, and exact description thereof, reference being had to the accompanying drawings, making a part of this specification, in which—like letters indicating like parts—

Figure 1 is a longitudinal sectional view of a locomotive fire-box, illustrative of my present improvements as applied thereto. Fig. 15 2 is a plan view of the fire-bed or grate-bars. Fig. 3 is a detached sectional view of the fuel-feeding mechanism, and Fig. 4 is a top or plan view thereof.

My present invention relates to certain improvements in apparatus or devices for preparing fuel for use in a locomotive fire-box, for feeding the same into the fire, and for promoting the combustion thereof. To these ends I make use of a hopper just outside the fire-door or feed-hole, the bottom of which hopper may be set or adjusted at an angle such that its slope or inclination shall facilitate or aid in feeding, but shall also have the capacity of holding or retaining the fuel in connection with a vertically-sliding or adjustable gate, by means of which latter the feed-opening may be enlarged or lessened at pleasure with reference to a slow feed, or may be shut down when no feed at all is desired; and I also provide an improved construction of inclined shaking-grate, whereby to secure a practically uniform distribution of the fuel in or on the fire-bed with reference to getting a maximum heating capacity.

40 In the drawings, A may represent the fire-box of a locomotive, surrounded by the usual water legs or jacket, A'. The fire-bed is formed by a series of sloping grate-bars, a c, of which the bars a are made hollow, and open at their opposite ends into the water-legs A', and the others of which, c, are solid, and of any desired form in cross-section. These latter at their backward ends—by which I mean the ends next the fuel-door B—are supported on a cross-bar, c', and may be held in place thereon by a downwardly-bent hook or lug, c'', on the end of each bar, which hooks onto the bar c'; or other

suitable means for this purpose may be employed. The opposite ends of the bars c rest on a rocking frame consisting of a transverse bearing-bar, b, supported at its ends by the arms b', and the latter are mounted on a pivot-shaft, b''. Spacing-collars a' are arranged on the bearing-bar b', so that one such projecting up between each two bars a c shall keep them 55 at the proper distance apart. On account of the slope of the feed-bed thus formed, the tendency of the fuel will be to slide down the slope; but as I propose to feed entirely or chiefly at the upper end of the slope, I use the mechanism thus described as a shaking mechanism, so as to aid in the movement of the fuel as it is gradually consumed down the slope of the fire-bed, and also to keep the fire clean and bright by shaking out ashes, breaking up and 60 removing the clinkers, &c.

As a means of effecting the shaking, I connect a crank-arm, n, to the pivot-shaft b'', so that as such arm is vibrated, it will impart an oscillatory motion to the shaking-frame b b' b'', 75 and thereby raise and lower the ends of the grate-bars c, which rest thereon. Such vibratory motion may be communicated to the arm n by any suitable mechanism extending from the cab, as from a lever, n', by connecting-rods n'' and bell-crank n'', as illustrated partly by full and partly by dotted lines in Fig. 1. When the fire-bed is to be entirely emptied or cleaned, the bolt or pin, which at n' connects the vertical rod n'' with the arm n, may 80 be taken out, and the shaking-frame may then drop down, so that the movable ends of the grate-bars c shall rest on the shaft b'', which will leave ample room for cleaning or discharging the entire contents of the fire-bed. 90

The fuel receiving and feeding mechanism is arranged just outside the fuel-door B. It consists of a hopper, D, the ends of which are formed by the plates d d, and the bottom by a plate, d', which latter is hinged by a rod, e, to 95 an angle-piece, d'', secured to the outside plates of the fire-box, or to the door-frame. The edges of the end plates, d, are bored, recessed, or slotted, as at e', so as to admit of the insertion of a bearing-rod, e'', by which to support the outer edge of the plate d', and thereby hold it at any desired position of adjustment or inclination with reference to utilizing such slope or inclination to aid in or facilitate the feeding

of the fuel deposited thereon through the door to the fire within; but still further to regulate this feed I use a vertically-sliding gate, *g*, which moves in grooves or ways *g'*, made in 5 or on the end plates, *d*, which gate may be raised or lowered to any desired position of adjustment by means of a handle, *h*. In order to hold it in the position of adjustment desired, I attach to or make on its back face a 10 rack, *s*, and just back of the rack, by means of a rod, *r*, pivot a pawl, *s'*, in such position that the gate may be raised at pleasure by operating the handle *h*, and may be lowered by like means, after turning the pawl out of engagement with the rack, which latter can be done 15 by the handle *r'*; but other suitable known form of device for securing the gate at any desired point of adjustment, and which permits of a change of adjustment, as may be desired, 20 may be substituted for the rack and pawl.

This mechanism is devised, chiefly, for use with locomotives wherein soft or bituminous coal is employed as the fuel, though it may be applied generally to all fire-boxes or furnaces 25 of substantially the same class, and wherever a constant or nearly constant feed of fuel to the fire-box is desired.

In ordinary practical use the fireman will 30 adjust his table or bottom plate, *d'*, and his gate *g* so that they will feed or facilitate feeding fast or slow, as may be desired. The fuel will then be shoveled into the hopper, and that portion of it next the fire-door will be rapidly heated, and if it remains long enough will be 35 coked or partially coked by the radiated and otherwise waste heat of the fire within. As the draft is uniformly inward, the smoke and gases given off from the fuel while in the 40 hopper will be drawn into the fire-box and consumed. As fast as the fire needs replenishing, it will work forward through the door, or the fireman will push it through slowly and in small quantities at a time, or rapidly, as occasion may require. The fuel so introduced 45 will be deposited at the upper end of the fire-bed, and the generation of gases will be more gradual and continuous than when coal is thrown upon the fire by the shovelful, as in the usual practice, thus enabling me to consume 50 the gases and prevent the formation of smoke by the small but constant supply of air which enters back of the sliding gate *g*, and by the variable supply which enters through the coal in the hopper. The gases given off 55 will be most effectually burned by the effect of the intense heat coming from below, and deflected back by the arch or roof plates *m*, and from which point, approaching a state of 60 incandescence as it goes, it will by the shaking mechanism be gradually worked down the

fire-bed to and help to make the hottest part of the fire.

The plate *d'*, forming the bottom of the hopper, may be fixed in place at a slight angle, if so desired, with good results; but I prefer to 65 make it adjustable, as described.

I am aware that apparatus embodying, in more or less complicated forms, combinations of certain of the devices employed in the practice of my invention has been heretofore 70 known, instances being illustrated in Letters Patent of the United States and Great Britain, and I do not, therefore, broadly claim the combination of a furnace feed-hopper and means for the movement and adjustment of its 75 bottom and end boundaries. So far, however, as my knowledge and information extends, the construction of such prior apparatus is not such as to render it of practical value in connection with the fire-box of a locomotive-engine, with a view to which application my improvements have been specially designed, and the same, as claimed, are limited to the specific novel combinations which I have devised 80 for effecting such application in a practical 85 and effective manner.

I claim herein as my invention—

1. The combination, with a fire-box, of a feed-hopper having an inclined bottom plate connected to a bearing or support on the fire-box shell, below and adjacent to the door-opening thereof, a plate fitted to move vertically in the feed-hopper in front of said opening, and a locking device which is secured to a shaft pivoted to the shell, above the door-opening, and is adapted to engage the adjacent side of the vertical plate, substantially as set forth. 95

2. The combination of a fire-box, a feed-hopper connected thereto adjacent to its door-opening, a downwardly and forwardly inclined 100 grate, the members of which are alternately fixed and movable, and mechanism for raising and lowering the movable members of the grate, adapted to be actuated from a point adjacent to the feed-hopper, substantially as set 105 forth.

3. The combination of a fire-box, a grate composed of a series of alternately-arranged fixed tubular bars and movable solid bars, an oscillating frame located beneath and supporting one end of the series of movable bars, and an operating-lever located adjacent to the door-opening of the fire-box and connected to said oscillating frame, substantially as set forth. 110

In testimony whereof I have hereunto set my 115 hand.

JOHN WILLS CLOUD.
